US00D421089S

United States Patent [19]

Fujita et al.

[11] Patent Number: Des. 421,089

[45] Date of Patent: ** Feb. 22, 2000

[54] WATER TREATMENT SYSTEM

[75] Inventors: **Tetsuya Fujita**, Kawasaki; **Kouichi Harada**, Yono, both of Japan[73] Assignee: **Amway Corporation**, Ada, Mich.[**] Term: **14 Years**[21] Appl. No.: **29/100,913**[22] Filed: **Feb. 22, 1999**[51] LOC (7) Cl. .... **23-01**[52] U.S. Cl. .... **D23/207**; D23/209[58] Field of Search D23/207-209;
210/435, 459-461[56] **References Cited**
